UNITED STATES PATENT OFFICE.

TURNER CLAY RUSH, OF LEXINGTON, KENTUCKY, ASSIGNOR OF ONE-HALF TO LESLIE B. INGELS, OF LEXINGTON, KENTUCKY.

WINDOW GUARD.

Application filed September 7, 1927. Serial No. 218,025.

My invention relates to an improvement in window guards. The present invention is more particularly intended as constituting an improvement on the window guard forming the subject matter of United States Letters Patent No. 1,450,117, granted to me March 27, 1923. In common with the aforementioned patented invention the present invention has for its general object to provide a window guard capable of adjustment to suit various sizes of window frames; to provide a window guard equipped with a novel means for effectively preventing the unauthorized removal of a guard from a window frame; and to provide a window guard that may be collapsed into small compass when not in use.

The specific object of the present invention is to improve the patented guard in various particulars having reference to the means whereby the locking bars forming part of the guard are locked together and the means for securing the collapsible guard to the window frame.

Reference is to be had to the accompanying drawings forming a part of this specification, it being understood that the drawings are merely illustrative of practical examples of the invention.

Figure 1 is a front elevation of a window guard embodying my invention showing the same secured in a window frame.

Figure 2 is a plan view, the window frame being in section as indicated by the line 2—2, Figure 1.

Figure 3 is an elevation of the window guard shown detached from the window.

Figure 3^a is a view partly in side elevation and partly in section of one of the headed pins or bolts and a key for turning the heads.

Figure 4 is a view similar to Figure 1 but showing another form of the invention.

Figure 5 represents a horizontal section on the line 5—5, Figure 4.

Figure 6 is a view partly in vertical section and partly in side elevation showing the end portions of the locking bars and the means for engaging the same with a window frame.

Figure 7 is a detail in vertical section on the line 7—7, Figure 4.

Figure 8 is a fragmentary side elevation showing a portion of my improved guard in another form.

Figure 9 is a longitudinal section through the lock for securing the locking arms.

Figure 10 is a transverse vertical section through the lock and locking arms shown in Figures 8 and 9.

Figure 11 is a perspective view of the flanged disk and fastening screw at the sill.

Referring at first more particularly to the form of the invention shown in Figures 1 to 3, a collapsible frame 10 is provided preferably in the form of lazytongs adapted to be distended to fit within a window frame 11. On certain of the end pins 12 in the bars of the lazytongs flanged disks 13 are mounted, the flanges of the disks having transverse holes therein to receive a screw 14 or equivalent fastener which thus passes through the flange into the material of the window frame 11. The provision of flanged disks and the transverse holes therein facilitates the emplacement and securing of the guard unobstructed by the presence of the fastener screws and avoids a particular manipulation of the guard members, as is the case where pivoted pins are provided on the guard to enter the window frame as in my patented construction.

I provide locking bars 15, 16 pivoted at their outer ends to the outer central pins 12 of the lazytongs, said bars being of a length to overlap each other and to be disposed in a position crossing the bars of the lazytongs. The one bar 16 has a longitudinal series of closely disposed pin holes 17 and in the other locking bar 15 a longitudinal series of pin holes 18 are provided and in the body of the bar 15 between its pivot pin 12 and the series of holes 18 I form oblong slots 19.

The overlapped bars 15, 16 when in the locking position as shown in Figure 1, extending directly across the bars of the collapsible frame 10, are received in a bracket 20 riveted to one of the bars of the frame 10 and disposed lengthwise therewith. The purpose of the holes 17, 18 and the oblong slots 19 is to provide for a minute and accurate adjustment of the frame 10 in fitting the frame to a given window space.

If holes were provided in lieu of the

oblong slots 19 the holes in the one bar 15 might not register with the holes 17 in the bar 16 in a given adjustment of the frame 10 whereas the provision of the oblong slots 19 in mesh with the holes 17 insures an engagement of a pin indicated at 21 in Figures 1 and 2 in a manner to hold the bars 15, 16 in rigid relation, thereby holding the frame 10 in a given adjustment. An additional pin 22 is passed through one of the series of holes 18 and one of the holes 17 at the same time that a pin 21 passes through a slot 19 adjacent to either end of the slot according to the adjustment of the frame 10.

15 The pins 21 and 22 are formed with rounded heads 121 as shown in Figure 3^a, the heads and the shanks of the pins having threaded engagement and said heads having holes 122 therein to receive a key A.

20 In the form shown in Figures 4 to 7 a collapsible frame 110 is fitted at least at the corners with described flanged disks 13 secured by pins 14 to the window frame. Locking bar 116 in this form of the invention is formed with a series of holes 117 and bar 115 is formed with a single pin hole 217 to receive a pin 221. The overlapped bars 115, 116 are received behind the described bracket 20. In the window frame 30 111 recesses 23 are produced and over said recesses escutcheon plates 24 are placed, said plates having holes 25 through which the ends of the respective bars 115, 116 are adapted to pass to partially enter the recesses 23.

35 An oblique slot 26 is formed in each bar 115, 116, adjacent the end thereof through which slot the central pins 112 of the collapsible frame 110 pass. Also, in the locking bars 115, 116 notches 27 are produced in the upper edges of said bars. By reason of the connection by the pins 112 at the oblique slots 26 the ends of said bars when the collapsible frame is fitted into the window frame 111, will be given such a movement as to cause the bars to engage the escutcheon plates at the notches 27 to positively engage said locking bars with the escutcheon plates and thus with the window frame. Latch members 28 are pivotally mounted on the bars 115, 116 and are adapted at their free ends to bear against the pins 112 when the collapsible frame 119 is fitted in the window frame 111, whereby to hold the collapsible frame rigid. The locking bar 116 is preferably given a U-shaped formation or staple formed at the end as at 29 to produce spaced sides fitting over the bar 115, said sides having registering holes 50 30 to receive the padlock 31.

55 The locking bars 115 and 116 are pivotally secured as at 215 and 216 to the collapsible frame 110 by bolts, rivets or the like.

60 In the form shown in Figures 8 to 10 the frame bars 310 arranged as in the form

of lazytongs as in the other constructions, instead of having locking bars at the center, are shown as provided with locking bars 315 and 316 pivoted to opposite sides at the top of the frame, said bars having the holes 17, 18 and slots 19. In the form of the invention shown in Figures 8 to 10 a lock case 32 has a hinged front cover 33 formed with an edge flange 34 overlapping the front edge of the case 32, the two being perforated to receive the bolt 231 of an interior lock 131 secured to the cover 33, the key of which is entered through a key hole 35 in the cover 33. Said casing 32 is held fast to the central pivot at the top of the lazytongs as by a rivet 36. When the cover 33 is lowered the bars 315, 316 are entered in the casing 32 and the front closed and secured by the lock 131. In practice, the locking bars may be disposed at the center, top, bottom, or in other suitable positions.

At the bottom of the guard, the flange of a lower disk 13 has a hole 37 therein best shown in Figure 11 and the screw 14 which is fixed in the window sill has a lateral head or bent upper end 114. In placing the guard in the window frame it is distorted or bent from its vertical plane sufficiently for the flange 113 to pass over the head 114, said head 114 passing through the hole 37 after which the guard is brought to the upright position in the window frame and thereby the engagement of the flange 113 with the head 114 of screw 14 will prevent the guard from being disengaged from the screw 14 by lifting the guard.

I would state in conclusion that while the illustrated examples constitute practical embodiments of my invention, I do not limit myself strictly to the exact details herein illustrated, since, manifestly, the same can be considerably varied without departure from the spirit of the invention as defined in the appended claims.

110 I claim:

1. A collapsible window guard having elements carried thereby at the sides thereof, said elements having transverse holes to receive fasteners for fastening the collapsible frame in a window frame.

115 2. A window guard formed of collapsible connected members, and flanged disks on said frame in position to bear against the window frame, the flanges of said disks having transverse holes to receive fasteners for securing the collapsible frame in a window frame.

120 3. A collapsible guard for window frames, means to lock said guard within the window frame, said means comprising locking bars each pivoted between its ends to the collapsible frame, said bars adapted to be overlapped, and a lock secured to the collapsible guard at one of the pivots thereof, said lock comprising a fixed casing, a hinged

cover on the casing, and a lock on the cover at the interior, said cover having a key hole leading to the lock and the cover and the body of the casing having perforations to

5 receive the bolt of the lock.

4. A collapsible window guard having a flanged disk at the bottom thereof, the flange of the disk having a hole, and a screw

having a head extending at one side of the axis of the screw, said screw adapted to be 10 driven into a window sill to engage the flanged disk at said hole.

Signed at Lexington in the county of Fayette and State of Kentucky this 2nd day of September, A. D. 1927.

TURNER CLAY RUSH.
